UNITED STATES PATENT OFFICE

OLE ALONZO LARSEN, OF SALT LAKE CITY, UTAH

DRAIN PLUG

Application filed January 22, 1930. Serial No. 422,568.

My invention relates to closure plugs and has for its object to provide a new and efficient plug for closing the drain holes of wash basins and other similar water containing devices which are drained from the bottom.

A further object is to provide a drain plug which may easily be attached therein, which may be quickly and easily removed if desired and which will normally be retained in the basin at all times.

A still further object is to provide a sanitary plug which has no part thereof in the water except the ring and in that way eliminates the accumulation of soap and dirty water on the chain.

A still further object is to provide a device which will keep the cross in the drain pipe clean at all times.

20 A still further object is to provide a drain plug which will be provided with depending means to engage with the cross in the drain pipe to hold the plug from engagement in the drain hole when it is desired to drain the basin and which depending means may be made of spring wire to give lasting qualities, to insure proper operation and to provide the means of retaining or removing the plug from the entire basin as 30 desired.

In apartments where the basins are used for small washings such as silk hosiery and other silks it is the practice to wash these things out by hand and with the old type 35 chain and plug the silks are often caught and torn or runs started in the woven fabrics. With my plug in the basin the chain is eliminated and the hand ring is made without corners and to lay down flat, providing 40 free space over the entire wash basin, thereby eliminating this danger to the goods being washed. Also in the washing with the chain plug type the chain is often jerked unintentionally draining the water from the 45 basin thereby wasting water. With my device this will never happen, thereby providing greater economy to the owner of the apartment or hotel as less water has to be heated.

50 These and many other objects I accomplish

with the device illustrated in the accompanying drawings in which similar numerals and letters of reference indicate like parts throughout the several views and as described in the specification forming a part 55 of this application and pointed out in the appended claim.

In the drawings in which I have shown the best and most preferred manner of building my invention Figure 1 is a section 60 of a portion of a basin with the drain pipe sectioned and my drain plug sectioned in place therein with the wire retaining means shown in elevation. Figure 2 is a side elevation of the drain plug. Figure 3 is a side 65 view of a drain plug with a vertical hand grip.

In the drawings I have shown the basin as A, the drain pipe as B, and the cross in the drain pipe as C. I then make a solid 70 rubber stopper plug 1, having two spaced apart holes 2 and 3 therethrough through which a spring wire 4 is passed. The wire 4 is bent into a ring 5 at the top end thereof through which a hand ring 6 is passed to enable the operator to raise the plug from the drain pipe when desired. The two legs 7 and 8 of the wire 4 are then passed down through the holes 2 and 3 of the plug and are crossed over at 9 and extended at 10 75 and 11 to approximately the same distance as the holes 2 and 3 on the opposite side. The legs are then bent to taper toward each other at 12 and 13 and are extended down to a point where they nearly meet at 20 80 where the legs are then bent outwardly again at 14 and 15 and the extreme ends are bent back inwardly with the ends turned upward at 16 and 17. In Figure 3 of the drawings the ring 5 is made large and 85 formed elongated to form a hand grip by which the plug may be removed should this type be more desired.

The dotted lines shown in Figure 1 indicate the position of the plug and the retaining wires when the plug is raised to allow the water to drain from the basin. The portion of the wires which is bent toward each other at the point 20 is drawn up over the cross C and the portions which are bent 90 95 L

out below 20 provide a space in which the cross may be moved around but the contracted portion 20 holds the plug raised. To close the plug the operator presses down on 5 the plug and the wire legs 7 and 8 will spring outwardly allowing the plug to be pressed down into place. To place the plug in the basin the two inwardly bent ends 16 and 17 are placed diagonally across the cross 10 and the plug is pressed down. This spreads the ends and allows them to pass over the cross. To remove the plug it is raised until the cross hits in the bends at the ends of the legs and the plug may then be twisted a 15 quarter turn which will spread the two ends apart and the plug may then be raised from the cross. The spring in the wires allowed at the bends 10 and 11 at the cross 9, in the holes 2 and 3 and in the ring 5 keeps the 20 wires from breaking and adds spring tension to the wires. This construction will provide a spring construction which will be so distributed over the entire wire as to eliminate any possibility of the wire breaking from constant springing causing crystallization of any one portion of the wire.

Having thus described my invention I desire to secure by Letters Patent and claim:—

- 30 In a closure plug for basins the combination of a solid closure plug having spaced apart holes therethrough; and having a wire bent into a ring and then having the legs thereof passed down through the said holes, 35 and having the ends crossed over, then bent inwardly to near each other and bent outwardly a short distance and curved back inwardly and upwardly to meet at the lower end.
- 40 In testimony whereof he has affixed his signature.

OLE ALONZO LARSEN.
